UNITED STATES PATENT OFFICE.

MARTIN WEISS, OF SAN MARCOS, TEXAS.

DESIGN FOR A MATCH AND CIGAR SAFE.

SPECIFICATION forming part of Design No. 27,739, dated October 19, 1897.

Application filed August 24, 1897. Serial No. 649,396. Term of patent 31 years.

To all whom it may concern:

Be it known that I, MARTIN WEISS, a citizen of the United States, residing at San Marcos, in the county of Hays and State of Texas, have invented a new and original Design for a Combination Match and Cigar Safe, of which the following is a specification.

This invention relates to a new and original design for a combination match and cigar safe; and it has for its object to provide a design of this character that shall be both useful and ornamental.

The leading feature of the design resides in a combination match and cigar safe having a main cubical box-base of a rectangular form and provided with a flat top, a smaller cubical body arranged on the flat top of the box-base and set back from the front edge thereof, and an upright rectangular column arising from the flat top of the smaller cubical body near the rear edge of the latter and provided with an inverted-V-shaped top portion, and a vertically-disposed spire projected upwardly from the apex of said top portion.

A minor feature of the design resides in providing the main cubical box-base in its front side with a rectangular drawer-panel and a pair of adjacent circular openings; the smaller cubical body with a rectangular drawel-panel in its front side; the inverted-V-shaped top portion of the column with molded edges overhanging the front side and ends of the column, and in forming the spire projection in a rectangular shape with a bead-flange surrounding its upper end.

In the drawings, Figure 1 is a perspective view of a combination match and cigar safe embodying the herein-described design. Fig. 2 is an end view thereof.

Referring to the accompanying drawings,

the numeral 1 designates the main cubical box-base of the safe, which is surrounded at its lower edge by a flange 2 of beaded molding and at its upper edge by a continuous overhanging bead 3. The said base 1 is provided in its front side with a rectangular drawer-panel 4 and a pair of adjacent circular openings 5, and the flat top 6 of the box-base 1 has arranged thereon a second cubical body 7. The cubical body 7 is smaller than the box-base 1 and is set back from the front edge of the latter with its rear wall flush with the rear wall of the base. The cubical body 7 is provided at its upper edge with an overhanging bead 8 with a flat top 9, and in its front wall or side with a rectangular drawer-panel 10, and arising from the flat top 9 of the body 7, at or near the rear edge of the latter, is an upright rectangular column 11. The upright rectangular column 11 is provided with beaded front corners 12 and with an inverted-V-shaped top portion 13, having molded edges 14, overhanging the front side and ends of the column.

The design is completed by providing the column 11 with a vertically-disposed spire 14, projected upwardly from the apex of the inverted-V-shaped top portion, and of a rectangular shape, with a bead-flange 15, surrounding its upper end.

What I claim is—

The design for a combination match and cigar safe, herein shown and described.

In testimony that I claim the foregoing as my own I have hereto affixed my signature in the presence of two witnesses.

MARTIN WEISS.
